ARRANGEMENT FOR RECEIVING TELEVISION IMAGES

Fritz Schröter, Max Knoll, Werner Klüge, and Hellmuth Etzold, Berlin, Germany, assignors to Telefunken Gesellschaft für Drahtlose Telegraphie m. b. H., Berlin, Germany, a corporation of Germany

Application May 27, 1937, Serial No. 145,020
In Germany May 27, 1936

10 Claims. (Cl. 178—7.5)

It is customary to employ Braun tubes in general for the reception of television images transmitted by means of a single transmission channel, for instance by means of a modulated carrier wave. Hereby, each image element is presented at the receiver side only during an extremely brief period when leaving out of consideration the after glow phenomena of the fluorescent screen. In view of such condition in the first place, the cathode ray in the Braun tube must be a very intensive ray, and furthermore, it is necessary to utilize a sufficiently large number of image alternations, and at the line skip method, a sufficiently large number of vertical alternations in order to reproduce the receiving image with sufficient freedom of flickering. The luminous current produced on the fluorescent mass unless extremely high voltages and amperages are used, is so low that it is necessary in general to view the television image at least in reduced daylight. The image on the fluorescent screen when projected on a surface having the size of a movie screen, i. e. a projection screen several m^2 in size cannot be obtained with the same brightness as in case of a movie picture even when using currents and voltages of high value.

In accordance with the invention, instead of reproducing the individual image points only at brief periods in the sequence in which they are received, there will be assigned to each image element a special cathode ray system having fluorescent screen and control grid, and during the entire time between two successive transmissions of brightness values assigned to the same image element, the control grid shall be maintained at constant potential, so that a constant current impinges on the fluorescent screen. Instead of assigning in this manner a cathode ray system having fluorescent screen and control grid to each image element, cathode ray systems may also be provided only for the image elements of the one image coordinate, while the other image coordinate is established by means of a suitable photo-optical arrangement for instance by means of an oscillating mirror or mirror wheel. In both cases, i. e. with a number of cathode ray systems corresponding to the number of image elements of the entire image, or only of an image coordinate, it is possible to view the fluorescent screen directly, or also the projection of the said screen.

The required potentials at the control grids of the cathode ray systems can be produced in the sense of the invention principally by means of any switch connecting the individual control grids in

succession with the amplifier of the receiver. In the examples of construction described in the following a cathode ray switch shall be utilized to this end, whose contacts are formed by the control grids of the cathode ray systems, and by controlling the current in the switching ray, the control grid potentials shall be determined by the balance between switch ray current and secondary electron emission current of the switch contacts (control grids).

Fig. 1 is a schematic diagram showing the method of operation of a cathode ray secondary emitter.

Fig. 2 shows the characteristic curves of the device shown in Fig. 1.

Fig. 3a shows an image reproducer in which the emission from a thermionic surface is controlled by a secondary emission surface.

Fig. 3b is a partial front view of the thermionic and secondary emission surface of Fig. 3a.

Figs. 4 to 9 are views of other modifications of the invention.

Before describing in detail the arrangement according to the invention and its functioning, there will again be reviewed the known facts regarding the secondary electron emission and the balance between primary current and secondary electron emission current upon which the invention is based.

In Figure 1, item 10 designates a glow cathode, 11 is a control cylinder, item 12 is an anode, and 13 is an absorption plate to which is imparted a high secondary emission capacity for instance by means of a cesium layer. Between the cathode 10 and the anode 12 a plate voltage source 14 is inserted and between the plate 13 and the anode 12, a direct voltage source U is placed. At the control cylinder 11 there is at first assumed a certain constant potential determining the ray current leaving the cathode 10 and which is assumed to pass in its entirety the anode 12. The current which can be measured in the line between the plate 13 and the voltage source U, varies in this arrangement in accordance with the value of the voltage U such as indicated in Figure 2. In Figure 2, the positive abscissa axis corresponds with the polarity of the voltage source U as indicated in Figure 1. The ordinate axis indicates the current that can be measured with the measuring instrument M. If the voltage U has the sign reversed as regards that indicated in Figure 1, a current flows only in the circuit designated by A, and the measuring instrument M indicates the same deviation m_1 as a measuring instrument m_2 in the lead-in to the

cathode 16. If the voltage U has a value that is not too low (for instance higher than 20 volts) and if it has the sign indicated in Figure 1, in addition to the current in the circuit A, an electron current flows through the circuit B since the secondary electrons produced on the plate 13 pass to the anode 12 acting as secondary emission anode. In the measuring instrument m_{11} the full value of this secondary emission current i_{s1} can be measured, while in the instrument M only the difference $i_{s1} - (i_{s1} - i_{p1})$ can be measured. If the voltage U decreases without at first changing the sign the secondary emission current i_{s1} will be decreased, finally assuming the same value as the primary current i_{p1} at the value $U=a$. In this case the instrument M points to zero. The entire curve 1 is then determined by a constant primary current i_{p1} , and constant secondary emission factor (measure of the number of secondary electrons produced by a primary electron) which is greater than 1. At another, i. e. larger primary current the curve 2 is obtained having the values i_{p2} , i_{s2} , i_{d2} . This curve 2 intersects the abscissa at a higher voltage U , namely $U=b$. The secondary emission factor for the curve 2 is the same as for the curve 1.

For a better understanding of the following, it should be kept in mind that the voltage U at which the curves 1 and 2 pass through the abscissa, is the higher the larger the primary current i_p . These voltage values are ordinarily termed balance potential of secondary emission, since the number of secondary electrons leaving the plate 13 is at these potentials equal to the number of primary electrons impinging on the plate. The potential of the plate 13 thus is the more negative relative to the secondary emission anode 12, the larger the primary current.

In the mode of construction represented in Figure 3a, a glass vessel 15 contains a cathode ray switch consisting of the cathode 16, a control cylinder 17, a first anode 18, a second anode 19 and switch contacts 20 to 22. Furthermore, there is accommodated within the glass vessel 15, cathode ray systems having fluorescent screen comprising the cathodes 23, 24 and a common anode 25 shaped as a grid embedded in the fluorescent substance 26. The contacts 20 to 22 of the cathode ray switch form at the same time the control grids for the individual cathode ray systems. The cathodes 23, 24 are connected to each other either in series (as shown in Figure 3a) or in parallel, and are passed by a heating current. The number of cathodes and control grids in the tube 15 may correspond to the number of image elements. As viewed from the side of the fluorescent screen the cathodes and control grids are situated for instance in the manner shown in Figure 3b. Between the first anode 18 and the cathode 16 a plate voltage source 27 is inserted, and a further plate voltage source 28 is placed between the second anode 19 and the first anode 18. Furthermore, a common plate voltage source 29 is inserted between the cathodes 23, 24 and the anode 25 common to all cathode ray systems. Regarding the value and polarity of the voltage source 30 between the second anode 19 and the cathodes 23, 24 it is referred to a later chapter.

The arrangement according to Figure 3a operates such that the voltage between the control cylinder 17 and cathode 16 of the cathode ray switch will be the more reduced the greater the brightness of the image point being transmitted at the moment. If in the usual manner dark

image points are transmitted by a small amplitude of the carrier wave, and bright points by a large amplitude, it is therefore necessary to provide a corresponding phase reversal before the image signals are passed to the control cylinder 17. The cathode ray, in the course of a deviation across the switch contacts or control grids 20 to 22 corresponding to an image line, thus varies its intensity inversely proportional to the brightness distribution along this image line. As explained on hand of the Figure 2, the individual contact elements and control grids therefore, assume potentials (namely the balance potentials) which are the more negative relative to the second anode 19 acting as secondary emission anode, the higher the amperage in the switching ray. Thus for instance, as long as the switch ray rests upon the contact element 20 and a dark image point is thereby transmitted into distance, the amperage of the switching ray is high, and the contact 20 therefore receives a comparatively high negative potential (for instance the value c in Figure 2) relative to the secondary emission anode 19. In respect to the cathode 23 having a low negative potential (the value c for instance in Fig. 2) determined by the voltage source 30 relative to the secondary emission anode 19, the control grid therefore, has a relatively high negative potential, so that from the cathode 23 no current or only a very small current passes to the respective place of the fluorescent screen 26. The fluorescent mass therefore, will not be energized at all or but slightly and consequently the dark image point will be correctly reproduced. If during the period in which the switch ray rests upon the contact element 21, a bright image point is to be transmitted, the amperage in the switch ray will be comparatively small, in accordance with the above, and the switch contact 21 thus receives only a low negative potential (for instance the value a in Figure 2) relative to the secondary emission anode 19. The control grid 21 thus has only a low negative potential relative to the appertaining cathode 24, and therefore a comparatively large current will pass from this cathode to the appertaining surface of the fluorescent screen in accordance with the corresponding brightness of the appertaining image point. Thus on the fluorescent screen 26 the television image will be reconstructed point by point, with the brightness corresponding with the carrier amplitudes transmitted into distance. Whether the voltage source 30 is to be chosen with the polarity indicated in Figure 3a (corresponding with the value c in Figure 2), or whether it be chosen with another value, and eventually with the reversed polarity depends on the construction of the individual cathode ray systems and in particular on the through grip of the anodes 29.

An arrangement according to Figure 3a may also be constructed with a number of cathode ray systems corresponding only to a single image line. The direct viewing or the projection of the fluorescent screen then takes place across moved mirrors or the like.

The mode of construction represented in Figure 5 differs from that according to Figure 3a substantially in that the individual cathodes are reproduced on the fluorescent screen 26 by means of an electron-optical reproducing device for instance a concentration coil 31.

As regards the setting of the control grid potentials by means of the switching ray whose intensity is controlled and which is deviated in

the coordinate, the arrangement according to Figure 5 operates in the same manner as that according to Figure 3a. The arrangement in the surface of the individual cathodes and control grids is shown in enlarged scale in Figure 4. The cathodes 23, 24 can be formed by filaments arranged in the manner of a cross shaped grid, whereby the contact elements and control grids 20 to 22 protrude through the openings of the grid.

In the mode of construction represented in Figure 6 the electron currents emanating from the individual cathodes likewise arranged in the manner of a mesh, are passed to the fluorescent screen by means of an electron-optical device in the same manner as in Figure 5. As compared with the Figure 5 this arrangement differs only insofar as the switching ray impinges on the control grids from the same side towards which 20 the electrons finally impinging on the fluorescent screen, leave the cathode.

In the arrangements according to Figures 7 to 9 in which likewise an electron-optical reproduction takes place on the fluorescent screen, the individual glow cathodes or parts of a common glow cathode are substituted by so-called virtual cathodes. This will at first be explained on hand of Figure 7. In this figure, the arrangement situated below the dot and dash line A—B is the same as in Figure 6. A grid 32 formed of metal has an insulating cover for instance of enamel whose bottom surface contains a large number of individual metal particles capable of secondary emission for instance composed of cesium. Above the line A—B an arrangement is provided for producing a diffused cathode ray beam impinging the entire surface of the grid 32. This arrangement consists of a cathode 33, a first anode 34, and a second anode 35 both of cylindrical shape. The voltage between the anode 35 relative to the cathode 33 is supplied by the direct voltage source 36 and is higher than the voltage of anode 34 originating with the direct voltage source 37. The grid 32 is connected to the cathode 33. The electrons penetrating the anode 35 at a high velocity are decelerated shortly before reaching the mesh-shaped electrode 32 forming at this place a space charge cloud acting directly as cathode. The anode 25 has a through grip through the meshes of the grid 32 thus being capable of withdrawing electrons from this space charge cloud, whereby the potential of the metal particles 20 to 22 acting as control grid, which potential is adjusted to by the switching ray, determines the electron quantity passing through each individual grid opening.

The arrangement according to Figure 7 may also be such that above the grid 32 a further grid electrode is provided having the same potential as the anode 35 in which case the retarding field for the production of the space charge cloud acts between the mesh-shaped electrode 32 and the grid situated above said electrode.

Moreover, in the arrangement according to Fig. 7 the switch ray tube and the tube for producing the diffused cathode ray beam may be interchanged also if only a single grid electrode 32 is provided, and likewise where a second grid electrode placed parallel to the first one, is provided. The arrangement for the last mentioned case is shown in Fig. 8 in which the second grid electrode is designated by 38. The retarding of the diffuse cathode ray beam originating with the cathode 32 takes place between the grid electrodes 32 and 38. The control grid elements

20 to 22 are situated in the meshes of the grid electrode 32.

In Fig. 9 a mode of construction is shown in which the arrangement for producing the diffuse cathode ray beam, the switch ray tube and the arrangement for the electron-optical reproduction on the fluorescent screen are all situated on the same side of the control grid elements arranged in a surface. A metal plate 39 is provided with an insulating covering and covered with metal particles 20 to 22 acting as control grid elements. The space charge cloud obtained by the retarding of the diffuse cathode ray beam is produced directly in front of the control grid elements, and the electron quantity impinging on each point of the fluorescent screen is influenced by the potentials assumed by the control grid elements owing to the changing amperage of the moving switch ray.

Also in the arrangements according to Figures 4 to 9, provision can be made that only the image of a single line appears on the fluorescent screen while the second image coordinate is produced by photo-optical means.

What we claim is:

1. A television reproducing device comprising means for developing an electron beam formation, means for deflecting said beam in at least one co-ordinate, means for modulating said beam in accordance with received television signals, means adapted to give off light under the impact of electrons thereon, a plurality of electron emission sources each for reproducing one element of the image to be reproduced in at least one co-ordinate, a plurality of individual grid elements interposed between said electron emitting sources and said means adapted to respond to electron impact, said grid elements having a high secondary emission characteristic, said grid elements being adapted to be impinged upon by the deflected electron beam formation whereby the potential thereof is governed by the equilibrium between the current of the deflected cathode ray beam and the secondary emission current of the individual grid elements.

2. Apparatus in accordance with claim 1, wherein each individual grid element is interposed between the plurality of electron emission means and the means responsive to electron impact, and is also positioned between the deflected cathode ray beam and the plurality of electron emission sources.

3. Apparatus in accordance with claim 1, wherein the plurality of electron emission sources comprises a plurality of virtual cathodes wherein electrons passing through the individual grid elements to the means responsive to electron impact are focussed thereon by electro-optical means.

4. Apparatus in accordance with claim 1, wherein the plurality of electron emission sources comprises a plurality of individual thermionic emitters.

5. Apparatus in accordance with claim 1, wherein said individual grid elements comprise a pair of planar faced members spaced apart by a conductor, one of said planar faces being apertured, the thermionic emitter associated therewith being positioned between the two planar faces.

6. A device for reproducing optical images in response to signals representative of said images, comprising means for developing an electron beam formation, means for deflecting said beam in at least one coordinate of movement, means for

modulating said beam in accordance with signals representative of the image to be reproduced, means adapted to give off light under the impact of electrons thereon, means for producing individual groups of electrons each for reproducing one element of the image to be reproduced, and a plurality of individual grid elements positioned adjacent said individual sources of electrons and adapted to have the potential thereof controlled in accordance with the value of the modulated cathode ray beam as it impinges thereon during its traversal.

7. Apparatus in accordance with claim 6 wherein there is provided in addition means for focussing each of the produced individual groups of electrons for producing one element of the image to be produced onto the means adapted to give off light under the impact of electrons thereon.

8. The method of reproducing an optical image which comprises providing a plurality of individual foci of electron emission each adapted to reproduce one incremental element of the image to be reproduced and continuously producing electrons, and controlling the emission from each of said foci sequentially in accordance with the equilibrium potential produced during the control of each of said individual foci by the action of a modulated electron emission.

9. A television reproducing device comprising means for developing a cathode ray beam, means for modulating said beam in accordance with the optical values of the image to be produced, means adapted to produce light under the action of electron bombardment thereon, a plurality of cath-

ode sources each for producing one of the image elements to be reproduced along at least one coordinate of said image, grid elements positioned adjacent said individual cathode sources and adapted to control the emission from said individual sources impinging on said light reproducing member, and means for directing the modulated cathode ray beam sequentially onto said grid elements whereby the potential of said grid elements is controlled by the action of said cathode ray beam thereon.

10. An apparatus for reproducing signals representative of optical images comprising means for developing a cathode ray beam, means for modulating said beam in accordance with the values of the image to be reproduced, means for producing a plurality of individual virtual cathodes each adapted to produce an electron emission for reproducing one element of the optical image to be reproduced along at least one coordinate thereof, means responsive to electron bombardment for reproducing light, said latter means being adapted to be impinged upon by the electrons from said virtual cathodes, a plurality of individual grid elements positioned adjacent said virtual cathodes and adapted to control the impingement of electrons from said virtual cathode onto said reproducing means, and means for directing the modulated cathode ray beam sequentially onto said grid elements.
